UNITED STATES PATENT OFFICE.

FRANK S. SHEFFLER AND CHARLES S. TURNER, OF NEWCASTLE,
PENNSYLVANIA.

CAR-COUPING.

SPECIFICATION forming part of Letters Patent No. 781,791, dated February 7, 1905.

Application filed October 10, 1904. Serial No. 227,903.

To all whom it may concern:

Be it known that we, FRANK S. SHEFFLER and CHARLES S. TURNER, citizens of the United States, residing at Newcastle, in the county of Lawrence and State of Pennsylvania, have invented certain new and useful Improvements in Car-Couplers; and we do declare the following to be a full, clear, and exact description of the invention, such as will enable others skilled in the art to which it appertains to make and use the same.

This invention relates to improvements in car-couplers.

The object of the invention is to provide an automatically-operating car-coupler the operative parts of which are on the outside, thereby obviating the necessity of providing a recessed or chambered draw-bar or coupler-head to receive said parts and permitting the use of a strong, durable, and solid construction of draw and head.

A further object is to provide a coupler so constructed and arranged that the knuckle pivot-pin will be relieved of the entire stress or pull, said stress being distributed between said pivot-pin and the lock-pin of the coupler.

With these and other objects in view the invention consists in certain novel features of construction, combination, and arrangement of parts, as will be hereinafter more fully described, and particularly pointed out in the appended claim.

In the accompanying drawings, Figure 1 is a top plan view of a coupler and draw-bar embodying the invention, showing in full lines the position of the knuckle when coupled and in dotted lines the position of the same when uncoupled and ready to be engaged by the coupler of the next car. Fig. 2 is a bottom plan view of the same. Fig. 3 is a longitudinal vertical sectional view on the line 3-3 of Fig. 1 looking in the direction of the arrow, the parts being shown in position ready for coupling. Fig. 4 is a detail perspective view of the knuckle removed from the coupler-head. Fig. 5 is a similar view of the locking-pin.

Referring more particularly to the draw-

ings, 1 denotes the draw-bar, on the outer end of which is formed a draw-head or coupler which is in the form of the Janney type, and consists of a fixed jaw 3 and a pivoted jaw or knuckle 4, said knuckle being connected to a head 2 by means of a pivot-pin 5. The knuckle 4 has formed thereon upper and lower inwardly-projecting tailpieces 6 and 7. The upper tailpiece 6 is in the form of a hook, which when said knuckle is in coupled position is adapted to engage the lug 8, formed on the upper side of the coupler-head. The lower tailpiece 7 is adapted to be engaged with the lug 9, formed on the lower side of said coupler-head, when the knuckle is in a coupled position. The engagement of said tailpieces 6 and 7 with the lugs 8 and 9 limits the inward movement of the knuckle when the same is brought to a coupled position.

In the outer end of the draw-bar 1 is formed a vertically-disposed rectangular aperture 10, in which is arranged a rectangular locking-pin 12. Said pin is provided with an offset head 13, whereby the same is prevented from slipping through said aperture 10. The corner of said locking-pin adjacent to the upper tailpiece 6 of the knuckle 4 is beveled or cut away, as shown at 14, so that when said pin is elevated in the aperture 10 said tailpiece is permitted to be moved past said pin, when the knuckle 4 is brought to a coupled or uncoupled position. When said knuckle is in an uncoupled position, the offset head of the pin 12 is adapted to rest upon the hook-shaped end of the upper tailpiece 6, which supports said pin in an elevated position until said knuckle is moved to a coupled position, at which time the tailpiece 6 will be swung from beneath the offset head of said pin, thereby permitting the latter to drop into position upon said draw-bar, thus automatically locking the knuckle in its coupled position.

On the end of the coupler-head 2, adjacent to the pivotal connection of the knuckle therewith, is formed a lateral offset or projection 15, which is adapted to be engaged by said knuckle when the same is swung to an uncoupled position, thereby limiting the out-

ward movement of the same, thus preventing the knuckle from being opened too far. On the upper and lower sides of the draw-bar 1, adjacent to the locking-pin 12, is formed off 5 sets or lugs 16, which are adapted to serve as stops, whereby the inward movement of the draw-bar, due to the concussion resulting from the coupling of the cars, will be limited.

By forming the knuckle of the coupler as 10 herein shown and described the operating parts of the same are adapted to work on the outer sides of the coupler-head, thereby avoiding the necessity of recessing or forming chambers in said head, as is usually done to 15 receive the operating mechanism, thus permitting the coupler-head to be formed solid. This construction of the coupler-head greatly increases the strength of the same and the draw-bar, so that the same is not liable to be 20 broken. The knuckle formed as herein shown and described is also of greater strength than those usually constructed and is not liable to become broken; but should a break occur in the coupler for any cause the knuckle will be 25 the part which will be broken, and should the knuckle be broken the same may be quickly and easily replaced with a new knuckle, a number of which will be carried by each train, thereby enabling the crew to quickly repair 30 a broken connection, whereas should the draw-bar or coupler-head be broken it would be necessary to remove the car containing such broken coupler to the shops for repair.

The locking-pin 12 may be elevated in the 35 aperture 10 in the ordinary manner or by any suitable mechanism. (Not shown.)

When the knuckle is in coupled position, the upper tailpiece of the same will be engaged with the head of the locking-pin and 40 will bear against the same when the coupler is in use, thereby relieving the pivot-pin of

the knuckle of the entire stress or strain of the cars.

From the foregoing description, taken in connection with the accompanying drawings, 45 the construction and operation of the invention will be readily understood without requiring a more extended explanation.

Various changes in the form, proportion, and the minor details of construction may be 50 resorted to without departing from the principle or sacrificing any of the advantages of this invention.

Having thus described our invention, what we claim as new, and desire to secure by Letters Patent, is—

In a car-coupler, the combination with a solid draw head and bar, of a knuckle pivotally connected to said draw-head, tailpieces formed on said knuckle to engage the upper 60 and lower sides of said head, said upper tailpiece provided with a hooked end, a beveled locking-pin arranged in said draw-bar, an offset head formed on said pin whereby when said knuckle is in an uncoupled position said 65 pin will be supported by the upper tailpiece of said knuckle in a position of release and when said knuckle is in a coupled position said tailpiece engaging the head of said pin thereby locking the knuckle in coupled position, and stop-lugs for the tailpieces whereby the opening movement of said knuckle is limited, substantially as described.

In testimony whereof we have hereunto set our hands in presence of two subscribing witnesses.

FRANK S. SHEFFLER.
CHARLES S. TURNER.
